UNITED STATES PATENT OFFICE.

CHARLES S. LAWRENCE, OF MOUNT LOWE, CALIFORNIA.

RATCHET TRIPOD-LEG.

1,093,866.

Specification of Letters Patent. Patented Apr. 21, 1914.

Application filed September 3, 1912. Serial No. 718,235.

To all whom it may concern:

Be it known that I, CHARLES S. LAWRENCE, a citizen of the United States, residing at Mount Lowe, California, have invented a 5 new and useful Ratchet Tripod-Leg, of which the following is a specification.

My invention relates to an improvement in adjustable legs for tripods of the kinds used for supporting photographic and scientific instruments.

The object of the invention is to provide a tripod leg which may be quickly and easily adjusted from one length to another and which will hold rigidly when finally adjusted. The means by which I have accomplished these beneficial results are set forth herein and are illustrated in the accompanying drawing in which;

Figure 1 is a front view of a tripod leg 20 equipped with my new features. Fig. 2 is a fragmental side view of the portion of leg containing my improvements. Fig. 3 is a vertical longitudinal section taken on the line *a—a* in Fig. 2. Fig. 4 is a transverse section taken at *b—b* in Fig. 3.

Throughout the several views like characters indicate like parts.

Referring to the details of construction 1 is a slidable member of a tripod leg.

20 2 is the member which serves as a guide for the part 1 and to which the part 1 is secured when the tripod is in use. In some tripods an additional folding member 3 connects the part 2 with the tripod head, in 35 other cases the part 2 is attached directly to said tripod head by any ordinary means.

This invention lies in the manner in which the parts 1 and 2 are locked in any desired relative position.

40 4 is a ratchet embedded in the side of the member 1. The number of teeth in this ratchet may be varied to suit the particular requirements of each case.

45 5 is a pawl pivoted in a slot 6 in the side of the member 2. This pawl actuated by a spring 7 engages the ratchet 4.

8 is a release socketed in the end of the pawl 5 and provides a means for releasing the pawl from the ratchet.

50 9 is a notch cut in the edge of the release 8. When the release is pressed inward and has raised the pawl from contact with the ratchet, it may be locked in this position by pushing the release upward and causing the

notch to engage the metal plate 10 through 55 which it operates, see dotted lines in Fig. 3. In this manner the member 1 is released and will remain released until the notch *a* is disengaged from the plate 10 and the release is pushed outward by means of the spring 7. 60

The use of the device is obvious from the foregoing description.

When the tripod is being leveled up, the 65 slideable members of the legs are released by means of the releases and are lengthened out to a length which may be expected to be approximately correct. The releases are then disengaged and the pawls engage the ratchets. The adjustment of each leg is 70 finally completed by withdrawing the member 1 or by depressing the release and pushing the member 1 upward.

The practical merits of this invention over the ordinary existing clamp means for securing the members 1 and 2 together will be 75 readily seen by any one acquainted with the use of tripods.

Having thus described my invention what I claim as new and desire to secure by Letters Patent is;

In a ratchet tripod, the combination with a plurality of upright sections extending substantially parallel in spaced relation, means for holding said sections in spaced relation, one of said sections being provided 85 with a longitudinally-extending slot leading from the outer side face and communicating with the space between the sections, a cover plate for the outer end of the slot in the section, a lower member slidably mounted in 90 the space between the sections of said upper member, a tooth rack bar carried by said lower member, a pawl pivotally mounted in said slot and having one end portion provided with a curved arm forming a substantially circular pocket, said pawl provided with a circular socket formed in one end thereof terminating in a substantially conical-shape entrance opening, a lever extending through said cover plate and provided 95 with a rounded inner end fitting in said socket, said lever provided with a neck tapering toward said rounded end adapted to work in said substantially conical-shape entrance opening for permitting said pawl to 100 be swung upon its pivot without binding upon the sides of said lever, said lever provided with a notch upon its upper end of the 125

same width as the thickness of said cover plate, said notch adapted to fit over said cover plate for firmly holding said lever against reciprocal movement, said lever provided with an enlarged head, said head being spaced from said notch for causing said head to be held in spaced relation relative to

said cover plate for facilitating the withdrawal of said lever through said cover plate.

CHARLES S. LAWRENCE.
